(73) Assignee: **Unicell Limited (CA)**

(57) **CLAIM**

The ornamental design for a vehicle rear door, as shown and described.

DESCRIPTION

FIG. 1 is a left side rear perspective view of the vehicle rear door;

FIG. 2 is a right side view of the vehicle rear door of FIG. 1;

FIG. 3 is a top view of the vehicle rear door of FIG. 1; FIG. 4 is a rear view of the vehicle rear door of FIG. 1; and, FIG. 5 is a front view of the vehicle rear door of FIG. 1. The left side view of the vehicle rear door of FIG. 1 is a mirror image of the right side view of FIG. 2. The portions of the vehicle rear door in broken line do not form part of the design.
